UNITED STATES PATENT OFFICE

GEORGE D. OVERHOLTZ, OF FAIR OAKS, PENNSYLVANIA, ASSIGNOR TO McCLINTIC-MARSHALL COMPANY, OF PITTSBURGH, PENNSYLVANIA, A CORPORATION OF PENNSYLVANIA

OUTDOOR ADVERTISING BULLETIN

Application filed April 21, 1930. Serial No. 445,945.

This invention relates to outdoor advertising structures, and more particularly to bulletins, as distinguished from poster panel constructions. In bulletin structures, as is well known in the art, the structure includes removable panels designed for having portions of the advertising applied directly to the individual panels, as by painting.

In such structures, it is frequently necessary to remove the panels therefrom, and one of the main objects of the present invention is to provide a bulletin of the character whereby the panels thereof may be readily removed from and applied to the structure with a minimum of trouble and expense.

In structures of the character under consideration, it is the custom to employ a surrounding molding usually comprising top, bottom and side molding sections, commercially designated cornice, sill and columns, respectively, and in the present invention, I have particularly illustrated the top and bottom moldings of such structures.

In the accompanying drawings, which illustrate an application of my invention:

Fig. 1 is a vertical sectional view showing a portion of an outdoor advertising bulletin embodying my invention;

Fig. 2, a perspective view particularly showing means for mounting the lower molding of the bulletin and a panel positioned therein; and

Fig. 3, a similar view showing the mounting swung into position to permit the removal of the panel sections.

Referring to the drawings, 5 designates the uprights of a steel frame employed for supporting moldings and other parts entering into the bulletin. This framing, in addition to the members 5, includes horizontally extending members 6 to which the panels, designated 7, are secured by means of L-bolts 8.

9 designates generally the upper molding mounting designed to receive the sheet metal upper molding A of the bulletin. As shown, the mounting includes an irregularly shaped member 10 having a portion 12 thereof secured to a Z-bracket 13, the latter being interposed between an upright 5 and the leg

portion 12. The Z-bracket is bolted, as indicated at 14, to the upright and is apertured, as at 16, to receive a horizontally extending bolt 17 having one end engaging the vertical member 5, and its opposite end passed through the aperture 16 and an opening in the leg portion 12. Interposed between and adjacent the said openings is a spacer plate or washer 18.

Secured to the inclined portion *a* of the member 10 by means of nuts and bolts 19, is a bracket 20. This bracket, in turn, is secured by a bolt 21 projecting from a member 5 to a Z-shaped bracket 22 extending from and secured to the upright 5.

Having a portion interposed between a part of bracket 20 and the bracket 22, is a horizontally disposed angle member 23 designed to extend substantially throughout the width of the upper molding; and positioned between portions *b* of member 10 and *c* of bracket 20 is a similar strengthening member 24. These members 23 and 24 add materially to the strength of the molding mounting, and it will be noted may be securely clamped and maintained in the desired positions between the respective adjacent portions above described, without the necessity of forming openings therein for the reception of bolts or other attaching means.

It will be understood that the metallic molding A may be readily applied to its supporting mounting, and when positioned thereon, it is fastened thereto by screw bolts 25.

The lower molding is indicated by B, and 26 designates an inverted U-shaped member, having one leg portion thereof secured to a Z-bracket 27 and the vertical member 5 by means of a horizontally extending bolt 28. A second U-shaped member 29 is associated with member 26 having its leg portions 30 and 31 overlapping and embracing the leg portions 26*a* and 26*b* respectively of the member 26.

It will be noted that the portion 31 of member 29 and the portion 26*b* of member 26 are each apertured, so that the openings thereof will come into alignment with an opening 32 of member 27, thereby enabling the bolt 28 to be passed through said openings, bolt 28.

being provided with a nut d for securely attaching the said members 26 and 29 to the Z-bar, and of course in turn to the vertical member 5. This construction, comprising members 26 and 29, provides a pivotally mounted bracket structure.

In addition to the parts just described, I provide a bracket member 33, said bracket member 33 being secured to the legs 26a and 30 by means of a bolt 34 passed through openings in the said members. A downwardly depending portion 37 of member 33 is adapted to receive the lower inclined edge portion of the molding B, and 38 designates a lock screw for securing the said lower edge of the molding B to the member 33. The upper portion 36 of the member 33 is parallel with the leg portion 26a of the member 26, but is spaced a short distance therefrom for receiving a horizontally extending strengthening member 39, which latter extends throughout the entire length of the molding B. Member 39 cooperates with the upper face of member 26 to form a flat receiving face for the upper portion of the molding B, to which the molding is secured by means of a screw bolt 40.

41 designates a box-like extension of the molding B and has an inner face or inner flange adapted to be positioned in contact with the outer faces of the lower portions of the panel sections.

The pivotally mounted bracket structure, including the members 26, 29 and 33, constitutes an efficient mounting for the lower molding B and also functions to support the lower edges of the panel sections 7 when the latter are positioned on the structure. This mounting provides for a ready application of the molding to the mounting and a removal therefrom and, in addition thereto, provides a construction enabling the panel sections to be removed and replaced with a minimum amount of labor and expense.

Assuming the parts are in the position shown by Fig. 1, and it is desired to remove the panel sections 7, all that is necessary to do is to remove the screws 38 and 40, loosen the nut d , and swing the bracket structure within the molding positioned thereon, from the position shown by Figs. 1 and 2 to the position shown by Fig. 3. This movement clears the brackets of the lower edges of the panels and permits the molding B to also drop below the edges of the panels to rest on said brackets, whereupon, the panels may be drawn towards the operator and upon freeing the bolts 8 may be lifted free of the structure. A replacement of the panels is easily accomplished, after which the molding is raised and the bracket structure swung therein into the position shown by Fig. 1.

I claim:

1. In an outdoor advertising structure, the combination with a supporting framing, panel sections, top and bottom molding

mountings, hollow metal moldings on said moldings, one of said moldings including a pivotally supported bracket structure positioned within a molding adjacent said panels and adapted to be swung to permit a removal of the panels.

2. In an outdoor advertising structure, the combination with a supporting framing, panel sections, top and bottom molding mountings, hollow metal moldings on said moldings, one of said moldings including a pivotally supported bracket structure positioned with a molding adjacent said panels and adapted to be swung within said molding to permit a removal of the panels.

3. In an outdoor advertising structure, the combination with a supporting framing, panel sections, a hollow top molding having a strengthening member disposed therein, a supporting bracket entered in the top molding and clamping the strengthening member, a hollow bottom molding having a strengthening member disposed therein, a supporting bracket entered in the bottom molding and clamping the strengthening member, one of said supporting brackets being pivotally mounted adjacent said panels and adapted to be swung to permit a movement of a molding to remove the panel.

4. In an outdoor advertising structure, the combination with a supporting framing, panel sections, a pivoted bottom molding mounting positioned adjacent said panels, a sill molding on said mounting, said mounting comprising a hollow bracket structure and a supplemental bracket member adapted for rotation within the sill molding.

5. In an outdoor advertising structure, the combination with a supporting framing, panel sections, a pivoted bottom molding mounting positioned adjacent said panels, a sill molding on said mounting, said mounting comprising a hollow bracket structure and a supplemental bracket member adapted for rotation within the sill molding, said bracket structure and bracket member having spaced-apart portions, and a strengthening member adapted to be entered between and clamped by said spaced-apart portions.

6. A sign structure comprising a supporting framework, a molding designed to be mounted on said framework, and means for securing said molding in position, said means comprising pivotally mounted members movable into or out of operative position.

In testimony whereof I affix my signature.
GEORGE D. OVERHOLTZ.

CERTIFICATE OF CORRECTION.

Patent No. 1,886,898.

November 8, 1932.

GEORGE D. OVERHOLTZ.

It is hereby certified that error appears in the printed specification of the above numbered patent requiring correction as follows: Page 2, line 78, claim 2, for "with" read "within"; and that the said Letters Patent should be read with this correction therein that the same may conform to the record of the case in the Patent Office.

Signed and sealed this 17th day of January, A. D. 1933.
